UNITED STATES PATENT OFFICE.

WALTER OSTWALD, OF GROSSBOTHEN, NEAR LEIPZIG, GERMANY, ASSIGNOR, BY
MESNE ASSIGNMENTS, TO THE CHEMICAL FOUNDATION, INC., A CORPORATION
OF DELAWARE.

METHOD OF PRODUCING NITROGEN COMPOUNDS DURING THE DRY DISTILLATION OF NITROGENOUS FUEL.

1,386,723.

Specification of Letters Patent.

Patented Aug. 9, 1921.

No Drawing. Application filed September 7, 1916, Serial No. 118,836. Renewed January 27, 1920.
Serial No. 354,748.

To all whom it may concern:

Be it known that I, WALTER OSTWALD, of
Grossbothen, near Leipzig, Germany, Haus
Dowa, have invented a certain new and use-
5 ful Improved Method of Producing Nitro-
gen Compounds During the Dry Distilla-
tion of Nitrogenous Fuels, of which the fol-
lowing is a specification.

During the dry distillation of a charge
10 composed of coal mixed with chlorids, it is
frequently found that in the pipes of the
plant thick tar-like masses are formed which
principally consist of ammonium chlorid
and cause serious trouble in the operation of
15 the plant. For obviating this defect it has
been customary to use so-called wet receiv-
ers in which the ammonium compounds in
question are carried away partly in aqueous
solution.

20 In the process according to my present in-
vention the opposite procedure is adopted.
The invention consists in converting the ni-
trogen at the outset uniformly into the
form of ammonium chlorid, so that it can be
25 readily condensed.

For this purpose, the nitrogen may, for
instance, be converted into ammonium
chlorid by the addition of chlorids to the
charge to be subjected to dry distillation.
30 The temperature of sublimation of am-
monium chlorid is about 450° C., so that it
can be readily separated from the gases by
fractional condensation.

My present invention, therefore, essen-
35 tially consists in converting into the form of
ammonium chlorid the entire nitrogen, which
can be obtained by the dry distillation of the
charge. The nitrogen contained in the coal
may be divided into two parts, namely into
40 one which may easily be obtained in a bound
form, that is the so-called non-fixed nitro-
gen, and into a second part which is not
liberated before the pyrogenous destruction
of the coke has started. This latter part
45 may be designated fixed nitrogen. The en-
tire amount of nitrogen is divided in ap-
proximately equal parts into fixed and non-
fixed nitrogen. In the process according to
my present invention only the non-fixed ni-
50 trogen can be obtained. It is, however, pos-
sible by means of my invention to prevent
the combustion of the nitrogen compounds

which are produced from the non-fixed ni-
trogen by converting the ammonia into am-
monium chlorid. The material increase in 55
the yield of nitrogen is thus partly ex-
plained. When the distillation is carried
out in the manner customary heretofore,
only 15% of the nitrogen of the coal can
be won, 50% of the nitrogen remaining as 60
fixed nitrogen in the coke and 15% in the
tar. The remaining part of non-fixed nitro-
gen (about 15% to 20% of the total nitro-
gen) can be obtained in the process accord- 65
ing to my present invention if care is taken
that the formation of ammonium chlorid is
not diminished owing to lack of water or
steam. In order to bind this remaining part
of the nitrogen which may be obtained dur- 70
ing the dry distillation in the form of am-
monium chlorid, according to my inven-
tion water or steam is introduced during
formation of the ammonium chlorid. This
water may consist of the moisture contained 75
in the coal, or a further addition of water
may be made, and the action may be en-
hanced by the water of hydrated salts; how-
ever, the preheating of the charge in the re-
torts should not be sufficient to expel, as 80
steam, the water added to supplement the
moisture contained in the coal. Owing to
the addition of chlorids and by regulating
the supply of water or steam, it is possible
to set free the two constituents of the am- 85
monium chlorid in such a manner that they
will be equivalent to each other at any mo-
ment of the carbonizing period. This is of
special importance, since an excess of free
ammonia might be decomposed by glowing 90
walls and since free hydrochloric acid is lia-
ble to injure the apparatus. The chlorids
used, may be the chlorids of the alkaline
earth metals or hydrochloric acid either in
liquid or gaseous form.

At the same time, obtaining the nitrogen in 95
form of ammonium chlorid has material ad-
vantages as regards the method of working
itself. Ammonium chlorid is uniformly
volatile, this being exactly contrary to most
other nitrogen compounds which have here- 100
tofore been found with the usual methods
in gas-water and in other constituents of the
distillation gases. By simply washing the
gas with water and cooling the solution to

the temperature of crystallization, it is possible to obtain directly, a pure marketable ammonium chlorid instead of the usual complicated mixture of various kinds of nitrogen compounds, all employment of sulfuric acid being dispensed with. The apparatus also is materially cheaper, especially because the treatment of the gas water and the apparatus for its saturation are dispensed with.

Another advantage with regard to the apparatus required due to the production of nitrogen in the form of ammonium chlorid is that the temperature of the scrubbing water may be raised to the boiling point, whereas in the production of ammonia water the scrubbing water must not have more than a predetermined very low temperature, requiring a complicated cooling apparatus.

The solution obtained by the present method is preferably evaporated in a neutral or slightly alkaline state, and this can be effected without material expense by waste heat, the ammonium chlorid being obtained directly in crystalline form. Lastly, obtaining the nitrogen in the form of ammonium chlorid has the further advantage that the chlorid can easily and cheaply be freed from impurities not only by recrystallization, but also by re-sublimation. Ammonium chlorid containing 25% nitrogen is richer in nitrogen than the ordinary commercial ammonium sulfate.

I claim:

1. In the dry-distillation or coking of a nitrogenous fuel, the process of obtaining as a by-product the non-fixed nitrogen of the fuel, which consists in mixing a chlorid with the fuel, in heating the mixture in a closed chamber and supplying steam thereto with the exclusion of air, whereby hydrochloric acid is produced and the nitrogen of the fuel is converted into the form of ammonium chlorid, and in subsequently separating the ammonium chlorid from the remaining products, substantially as described.

2. In the dry-distillation or coking of a nitrogenous fuel, the process of obtaining as a by-product, the non-fixed nitrogen of the fuel, which consists in mixing a chlorid with the fuel, in heating the mixture in a closed chamber and supplying steam thereto with the exclusion of air, the quantity of admixed chlorid being approximately equivalent to the percentage of non-fixed nitrogen in the fuel, whereby hydrochloric acid is produced and nitrogen of the fuel is converted into the form of ammonium chlorid, and in subsequently separating the ammonium chlorid from the remaining products substantially as described.

3. In the dry distillation or coking of a nitrogenous fuel, the process of obtaining as a by-product, the non-fixed nitrogen of the fuel, which consists in mixing a hydrated chlorid with the fuel, in heating the mixture in a closed chamber and thereby generating steam therein with the exclusion of air, whereby hydrochloric acid is produced and nitrogen of the fuel is converted into ammonium chlorid, and in subsequently separating the ammonium chlorid from the remaining products, substantially as described.

4. In the dry-distillation or coking of a nitrogenous fuel, the process of obtaining as a by-product, the non-fixed nitrogen of the fuel, which consists in mixing a chlorid with the fuel, in heating the mixture in a closed chamber and generating steam therein with the exclusion of air, whereby hydrochloric acid is produced and the nitrogen of the fuel is converted into ammonium chlorid, and in subsequently scrubbing the gases produced with water and thereby obtaining the ammonium chlorid in the form of an aqueous solution, substantially as described.

In testimony whereof I affix my signature in presence of two witnesses.

WALTER OSTWALD.

Witnesses:

RUDOLPH FRICKE,
THEKLA FRICKE.
